UNITED STATES PATENT OFFICE.

JOHN C. KAPPELHOFF, OF ST. PAUL, MINNESOTA.

BOTTLE-CAPPING MACHINE.

1,296,810.

Specification of Letters Patent. Patented Mar. 11, 1919.

Application filed September 4, 1917. Serial No. 189,652.

To all whom it may concern:

Be it known that I, JOHN C. KAPPELHOFF, a citizen of the United States, residing at St. Paul, in the county of Ramsey and State 5 of Minnesota, have invented a new and useful Bottle-Capping Machine, of which the following is a specification.

My invention relates to bottle capping machines, and the object is to so construct the 10 machine that as compared with the ordinary bottle-capping machines my device will considerably reduce the cost of making and of operating the machine and also breakage of bottles during the operation of capping 15 them.

In the accompanying drawing, Figure 1 is a diametrical vertical section of one of the bottle supports and a radial section of fragments of the rotary frame holding the 20 bottle supports. At the base of this view is shown a portion of the fixed cam that causes each bottle support to raise at a certain point of its travel. Fig. 2 is the top portion of the support shown in Fig. 1 with a bottle 25 upon it and a diametrical section of the casing and plunger above the bottle. Said view may also be considered as an upward continuation of Fig. 1. Fig. 3 is a detail side view of the plunger in the upper part 30 of Fig. 2 on an enlarged scale. Fig. 4 is a cross section on the line 4—4 in Fig. 3.

Referring to the drawing by reference numerals, 1 designates the filled bottle which is to receive a metal cap 2 with a thin layer 35 of cork within it by which the bottle is closed when the cap gets its edges squeezed downward and slightly inward under the regular top collar of the bottle neck. Such process of capping bottles, and the capping machine in general, are so well known that I 40 need not go into details about the same, but will merely mention that in Fig. 1, 3 designate portions of the usual double spider rotated on a vertical post (not shown) and 45 carrying a series of vertically movable slides, 4, each of which has its upper end provided with a guard 5 by which to move the bottle 1 along while it is supported upon a rubber cushion 6 fixed in a cavity in the top of the slide. 7 are keys fixed in the slide and engaging loosely in key ways in the spiders of the carrier drum to prevent rotation of the slides as they revolve about the post (not shown). The lower end of each slide or bot- 50 tle support 4 is provided with a roller 8, which rolls on a circular track 9, the latter

having at one point an elevation or cam 10 by which to raise the slide as it approaches the point where the bottle is to be capped. To prevent a jumping action of the slide it 60 is also provided with a small roller 11 which engages under a flange 12 of the cam 10.

As the slide 4 passes over the cam 10 the bottle 1 is thereby pushed with its top upward into the throat 13 of a casing 14, which 65 is mounted on the central post of the machine and receives through a lateral mouth 15 the partly prepared caps 2, which are fed from a hopper (not shown).

Suitably retained in the upper part of the 70 throat 13, above the mouth 15, is a capping plate 16 having a central taper throat 17 designed to close the caps about bottle necks of different diameters by allowing the smaller necks to raise that much higher into the 75 throat of the plate.

To raise the bottles into said position in the throat and thereby close the caps without breaking the bottle, the bottle support is made up of telescoped sections 4, 4^a and 80 4^b, the latter being an outer sleeve of part 4^a, to which it is threaded at 18, and between the adjacent ends of sections 4 and 4^a is interposed a partly compressed spring 19, which is of sufficient stiffness to cause the 85 crimping of the cap about the bottle neck and also to compress the two springs (presently to be described) which are located above the bottle.

Guidingly inserted in the slide member 4^a 90 and in the spring 19 is a tubular member 20 having at its lower end a collar 21, which is guided in the member 4 and supports the lower end of the spring 19 indirectly upon the top of a cylindrical hollow member 4^b, 95 which is loosely placed within the member 4 and forms by its internal open space 22 a clearance for the nuts 23, of a rod 24, which has its upper end threaded at 25 into the top section 4^a; said rod and nuts serving 100 to regulate the normal expansion of the spring 19.

Turning now again to the casing 14 and the springs therein, it will be noted that the spring 26 bears upon the collar 27 of a 105 plunger 28, whose lower end and said spring serve to eject the capped bottle downward from in the throat 13—17.

In the cavity 29 in the upper end of the plunger is a small but comparatively stiff 110 coil spring 30 which is normally partly compressed by the end of a tension screw

31 having a jam nut 32 to secure it in the desired position. In Fig. 2, 33 is a set-screw holding a collar 33^a which has an opening toward the mouth 15. Said collar as well 5 as the collar or plate 16 are inserted from below and supported by the annular throat collar 13 the latter being threaded at 34 to the casing 14. In Figs. 3 and 4 is shown how the plunger 28 is comparatively light 10 but provided with ribs 28^a so as to fill and guide the spring 26.

In the operation of the machine the spring 19, when raised by the cam 10, although it is only about half as strong as in earlier 15 machines, raises the bottle support and bottle with ease against the resistance of the much lighter spring 26 until the spring 19 becomes compressed enough to close the cap. At this point of operation the roller 8 is 20 passing over the top of the cam 10 and thus finds so little resistance in its forward movement that the slight raising movement of it is very powerful, and by its force compresses the spring 30, which is stiffer than 25 the spring 26, and finishes the closing of the cap. This upward force will often cause the cap to stick in the throat 17 so that it takes an extra strong force to start it downward again. This extra force is then furnished by the expansion of the spring 30 30 the moment the bottle starts on its downward movement, and after it is started downward the spring 26 will further act on the plunger to cause the bottle to leave the 35 throat without any jar or chance to tumble from the support until it reaches the regular means by which it is removed. If the bottle neck is extra small the spring 30 may 40 get compressed to its limit and form a positive stop, but even if this does not take place the final compression of so stiff a spring forms a comparatively positive yet yieldable pressure in the capping and ejecting process, and this without requiring the ex-

pensive features used in earlier constructed 45 machines, in which the member corresponding to my element 4^b is a two part dash-pot with a heavy spring between the two members, and the spring corresponding to my 50 spring 19 is about twice as large and stiff as my spring, and so is the spring in the casing 14, all of which requires a wasting of material and labor and of power in the operation of the machine.

I am aware that prior to my invention 55 attempts have been made to give the plunger 28 a positive stop in its upward movement at the moment the cap is fully closed in the throat, but as this is impractical due to the fact that some bottle necks are smaller 60 and should pass farther up so as to get the cap fully closed I do not use nor claim a positive stop at any certain point.

What I claim is:

In a bottle capping machine, a bottle support consisting of a vertically slidable plunger having closed top and bottom and composed of two telescoped tubular sections and a hollow support upon the bottom of the lower section, a tubular inner member 65 slideable with its upper portion in the upper section and having about its lower end a fixed collar slideable in the lower section and arranged to rest upon the hollow support; a partly compressed coil spring inserted 70 between the said fixed collar and the bottom end of the upper plunger section; a rod secured with its upper end in the top closure 75 of the upper plunger section and having on its lower end threaded a nut arranged to bear up under the member having the collar, and means preventing accidental turning of said nut; said hollow support having a clearance for said lower end of the rod 80 and the nut on same. 85

In testimony whereof I affix my signature.

JOHN C. KAPPELHOFF.
